UNITED STATES PATENT OFFICE.

JETHIRO J. RICE, OF GRAND RAPIDS, MICHIGAN.

DESIGN FOR A BUREAU, &c.

SPECIFICATION forming part of Design No. 23,928, dated January 1, 1895.

Application filed September 17, 1894. Serial No. 523,282. Term of patent 7 years.

To all whom it may concern:

Be it known that I, JETHRO J. RICE, a citizen of the United States, residing at Grand Rapids, in the county of Kent and State of Michigan, have invented and produced a new and original Design for a Bureau or Analogous Article of Furniture, of which the following is a specification, reference being had to the accompanying drawing, in which I have illustrated my design in a bureau and in which the figure is a perspective view.

The leading feature of my design consists in a bureau or analogous article of furniture the side ends of the body of which are formed with or in a double or ogee curve.

In the drawing the reference-numeral 1, indicates a bureau the side ends of the body

whereof are formed with or in a double or ogee curve, the numeral 2, indicating the convex portion and 3 the concave portion of said double or ogee curve. Ornamental moldings or borders 4 and 5, are arranged at the upper and lower extremities of the side ends of the case.

What I claim is—

The design for a bureau or analogous article of furniture herein shown and described.

In witness whereof I have hereunto set my hand and seal in the presence of two witnesses.

JETHRO J. RICE. [L. S.]

Witnesses:

ARTHUR C. DENISON,
CHRISTOPHER HONDELINK.
